(57) **CLAIM**

The ornamental design for a modular LED light housing with an adjustable surface mounting, as shown and described.

DESCRIPTION

FIG. 1 is a perspective view of a first embodiment of a modular LED light housing with an adjustable surface mounting;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof;

FIG. 8 is a perspective view of a second embodiment of a modular LED light housing with an adjustable surface mounting;

FIG. 9 is a front elevational view thereof;

FIG. 10 is a rear elevational view thereof;

FIG. 11 is a left elevational view thereof;

FIG. 12 is a right elevational view thereof;

FIG. 13 is a top plan view thereof; and,

FIG. 14 is a bottom plan view thereof.
